UNITED STATES PATENT OFFICE.

WILLIAM LAMB, OF DOWNEY, CALIFORNIA.

COOKING-STOVE.

SPECIFICATION forming part of Letters Patent No. 406,051, dated July 2, 1889.

Application filed August 13, 1888. Serial No. 282,577. (No model.)

To all whom it may concern:

Be it known that I, WILLIAM LAMB, a citizen of the United States, residing at Downey, in the county of Los Angeles and State of California, have invented a new and useful Improvement in Cooking-Stoves, of which the following is a specification.

My invention relates to that class of cooking-stoves in which the flues are so arranged that the flame may be made to encircle the oven or may be made to pass out of the smoke-outlet immediately after passing over the top of the oven.

The object of my invention is to secure complete control of the heat by simple and easily-constructed flues and dampers, as will hereinafter more fully appear.

My invention consists in the peculiar arrangement and combination of flues, partitions, and dampers, which control the flame and cause it to pass to the portion of the stove desired to be heated.

The accompanying drawings illustrate my invention.

Figure 1 is a view of the top of the stove provided with my invention, the position of the partitions and dampers being indicated by dotted lines. Fig. 2 is a plan view showing the top of the stove removed. Fig. 3 is a longitudinal vertical mid-section on line $x-x$ in Fig. 1. Fig. 4 is a vertical cross-section on line $y-y$ in Fig. 3, looking toward the rear of the stove. Fig. 5 is a vertical cross-section on line $z-z$ in Fig. 3, looking toward the front of the stove. Figs. 3 and 5 are broken to contract the view.

The size and proportion of the stove and oven shown are not features of my invention and are non-essential.

In stoves of this class it is customary to surround the oven at its top, rear, bottom, and front with smoke and flame passages. I divide the top one of these passages into three flues C, E, and E' by partitions F F', extending from the fire-box A to the rear wall of the stove. The front ends of these partitions are connected by a partition G, which separates the middle flue C from the fire-box. The side flues E E' open directly from the fire-box, and are separated from the ascending flue B'' by the partitions M M'. The rear ends of the side flues E E' open into the

descending flue B, and their passages are controlled by dampers I I'. The central flue C opens into the descending flue B, and the smoke-outlet D is arranged immediately above the junction of the two flues. The partitions F F' extend across the flue B to the rear wall L, and the lower edge of the partitions slope from the top of the oven upward to the rear wall of the stove to correspond with the lower side of the damper H when it is thrown back against the rear wall, as shown in Fig. 3. This is to give freer passage for the smoke and flame between the flue E and the smoke-outlet D when the damper is turned to close the flue C. The damper H is mounted on the rear upper corner of the oven, and is arranged to turn both upward and backward. When turned upward, it comes into contact with the top plate N and closes the flue C in front of the smoke-outlet D. It is shown in this position in Fig. 1, and such position is also indicated by dotted lines in Fig. 3. When the damper H is turned back, it rests against the rear wall L and closes the flue C at its junction with the descending flue B below the outlet D.

When it is desired to heat the oven and also the top of the stove, the dampers I I' are thrown down to open the flues E E', and the damper H is thrown back against the wall L to close the opening between the flue C and the descending flue B. The flame and heat then passes from the fire-box through the flues E E', beneath the pot-holes J, thence down the descending flue B, along the bottom flue B', up through the ascending flue B'', along the flue C, and out through the smoke-outlet D. The pot-holes J, which are arranged in the top N above the flues E E', thus receive the full heat of the flame, and each of the four sides of the oven receives a portion of the heat. The descending, bottom, and ascending flues are respectively co-extensive with the rear, bottom, and front of the oven, and the flues E E' C together cover the top of the oven. The side flues E E' are wide enough to receive the pot-holes J in their top, and the central flue C is wide enough to allow free passage of the flame and smoke.

If it is desired to turn all the heat into one of the flues E E', one of the dampers I' I is

thrown up to close its flue. If it is desired to pass the flame out without heating the oven, the damper H is raised to close the flue C in front of the outlet D. This leaves a free opening from the flue B upward to the outlet D, and the flame and smoke, as it issues from E E' into D, dives under the sloping bottom edges of the partitions F F' and rises to pass out through D without passing round the oven.

Now having described my invention, what I claim as new, and desire to secure by Letters Patent, is—

In a stove such as described, the combination, set forth, of the oven, fire-box, and walls of the stove, the two side flues E E', leading from the fire-box A across the top of the oven, the descending flue B, coextensive

with the rear of the oven, the bottom flue B', coextensive with the bottom of the oven, the ascending flue B'', coextensive with the front of the oven, the middle flue C, connecting the ascending flue B'' with the smoke-outlet D and the descending flue B, the smoke-outlet D, arranged above the junction of the flues B and C, the partitions M M', separating the flues E E' from the ascending flue, the partitions F, F', and G, the dampers I I', arranged to close the flues E E', and the damper H, arranged to close the flue C in front of and below the outlet D, as and for the purpose set forth.

WM. LAMB.
